UNITED STATES PATENT OFFICE.

THOMAS WYATT AND JASON F. HOLMES, OF PROVIDENCE, RHODE ISLAND.

FIRE-ESCAPE LADDER.

SPECIFICATION forming part of Letters Patent No. 280,433, dated July 3, 1883.

Application filed February 19, 1883. (No model.)

To all whom it may concern:

Be it known that we, THOMAS WYATT and JASON F. HOLMES, both of the city and county of Providence, in the State of Rhode Island, have invented certain new and useful Improvements in Fire-Escape Ladders; and we do hereby declare that the following specification, taken in connection with the drawings furnished and forming a part of the same, is a clear, true, and complete description of our invention.

Our said improvements relate to that class of jointed or folding fire-escape ladders which are capable of ready transportation from point to point within a building, or of being permanently located adjacent to upper windows; and the objects of our invention are to provide for the safe descent by timid persons, for convenient access to and from the fire-escape at various points thereon when set for use, and generally to render the same compact when not in use, readily adjusted for service, and to produce the same economically, having due reference to strength and durability.

After fully describing a fire-escape embodying our improvements, the features deemed novel will be specified in detail in the claims hereunto annexed.

Referring to the drawings, Figure 1 is a side view of one of our fire-escapes folded and mounted on a truck as for use in the halls of a hotel. Fig. 2 is a side view of the same in its extended position, as for use from an upper window of a building, the latter being shown in section. Fig. 3 is an enlarged side and sectional view of several joints of said fire-escape, illustrating the construction thereof. Fig. 4 is a side view of another form of fire-escape involving certain features of our invention.

It will be understood that our fire-escape ladder is kept in a folded condition when not in use, and, instead of being mounted upon a truck, as shown, it may be kept near a window, upon the floor of a hallway or room, or on a shelf provided therefor, and provided with a strong cross-bar longer than the width of the window, to serve as an anchor or stay for the upper end of the ladder, by passing said rod through suitable holes near the ends of the upper links, *a*, of the side bars, *A*, said upper links being long enough to properly overlie the window-sill. Each side bar, *A*, is com-

posed of a series of links, *a*, each of which is a little longer than one-half the distance between the rounds *b*, which are preferably composed of a piece of metal tubing, and an interior wire or rod, which at each end serves as a headed pivot for flexibly uniting the links *a* at alternate joints; but, instead of the interior rod, the tubular rounds may be tapped at each end and screws employed as pivots. The intervening joints of the links *a* are pivoted by the shank of an eyebolt, *c*.

To afford a good foothold on the rounds when the ladder is in position against a wall for use, wall-braces composed of links *d* in pairs are pivoted to each other at one end, and at their other ends to the adjacent rounds *b*, or to their pivot-screws, as the case may be; and as these wall-brace links are longer than the side links, *a*, of the ladder, they form, when in use, rigid triangular braces, which, adjacent to their outer pivots, bear against the wall, and thereby maintain the ladder at a proper distance from the wall of a building to afford a good foot-bearing upon all of the rounds. Wall-braces of various kinds have heretofore been employed in folding ladders.

The safety-guards *e* are U-shaped, and extend from either side bar forward across the front of the ladder and back to the other side bar, thus inclosing a vertical space in front of the ladder ample to receive a person in making a descent. Safety-guards have heretofore been employed on permanently mounted, and also on flexible or jointed, ladder fire-escapes; but we know of none prior to our invention which have been so organized with jointed ladders that when in position for use each guard is individually maintained in a horizontal position, instead of being supported at their outer ends, as heretofore, by means of a pendent cord or chain common to them all; and although we have illustrated two methods of constructing the same, we deem that shown in Fig. 1 to be the most desirable. Each safety-guard of the preferred form is pivoted at each of its ends to the apex-pivot *f* of a pair of the wall-braces *d*, and it freely occupies at its sides the adjacent eyebolts *c*, so that these latter serve to maintain each safety-guard in a horizontal position when in use, and they also serve to properly control said guards when the ladder is in a folded condition.

(No Model.)
